Top 10 Best Microwave Egg Poachers: Announced Jun. 2016 [online], site visited Dec. 18, 2016]. Available from Internet URL: <https://www.alltopbest.com/home-kitchens/top-10-best-microwave-egg-poacher-reviews/>.*Primary Examiner — Barbara Fox*Assistant Examiner* — Catherine S Posthauer(74) *Attorney, Agent, or Firm* — Millen, White, Zelano & Branigan, P.C.(57) **CLAIM**

The ornamental design for an egg poacher, as shown and described.

DESCRIPTION

FIG. 1 is a top perspective view of the egg poacher showing my new design.

FIG. 2 is a bottom perspective view thereof.

FIG. 3 is a side view thereof.

FIG. 4 is another side view thereof.

FIG. 5 is a top view thereof.

FIG. 6 is a bottom view thereof.

FIG. 7 is a top perspective exploded view thereof.

FIG. 8 is a bottom perspective exploded view thereof; and,

FIG. 9 is a side exploded view thereof.

(Continued)

The broken lines in the drawings illustrate portions of the egg poacher which form no part of the claimed design.
